(57) **CLAIM**

The ornamental design for a wall board attachment lug, as shown and described.

DESCRIPTION

FIG. 1 is a front view of a wall board attachment lug;
FIG. 2 is a back view thereof;
FIG. 3 is a top plan view thereof;
FIG. 4 is a bottom plan view thereof;
FIG. 5 is a right side view thereof;
FIG. 6 is a left side view thereof;
FIG. 7 is a perspective view thereof; and,
FIG. 8 is another perspective view of the wall board attachment lug of FIG. 1, shown in a configuration of use.
The broken lines in FIG. 8 represent environmental subject matter only and form no part of the claimed design.

1 Claim, 8 Drawing Sheets
